UNITED STATES PATENT OFFICE

115,098

DESIGN FOR A DISPENSER FOR INTER-FOLDED SHEETS

Frank L. Broeren, Neenah, Wis., assignor to Marathon Paper Mills Company, Rothschild, Wis., a corporation of Wisconsin

Application March 10, 1939, Serial No. 83,491

Term of patent 14 years

To all whom it may concern:

Be it known that Frank L. Broeren, a citizen of the United States, residing at Neenah, Winnebago County, in the State of Wisconsin, has invented a new, original, and ornamental Design for a Dispenser for Interfolded Sheets, of which the following is a specification, reference being had to the accompanying drawing, forming a part thereof.

Figure 1 is a perspective view of a dispenser for interfolded sheets, showing my new design;

Figure 2 is a side elevational view thereof, on a reduced scale;

Figure 3 is a top plan view; and

Figure 4 is a front elevational view.

I claim:

The ornamental design for a dispenser for interfolded sheets, as shown.

FRANK L. BROEREN.
